ABSTRACT OF THE DISCLOSURE

A priority sequence storage device for writing priority information from an external memory into a memory array in the order of priority of the incoming words, the priority of which is represented by a combination of priority bits and characterized in that a word of given priority already stored in the memory array takes precedence over an incoming word of the same priority, wherein a control level is supplied to the memory array and is caused to travel through said array along a path, and to emanate from said array at a position, which path and position depends upon the relative priority of the external information and any information already stored in said memory array so that the incoming words are written in the proper order of priority into said memory array and so that priority words in said memory array can be read out in the order of priority.

BACKGROUND OF THE INVENTION

In data processing applications it often is desirable to store items of information in the storage location in the order of priority. In many instances, the priority order has been established by the programmer. Such a software approach can result in complex programs which may have to be revised with changes in incoming information. In accordance with the invention, the information is written simply and inexpensively into the storage array in order of priority and the information can be read out quite simply in the proper order. This hardware approach is preferable to the programming approach and to certain systems of the prior art in which the information is written into storage in random fashion and then must be retrieved in order of precedence by somewhat elaborate and time-consuming controlled searching techniques.

SUMMARY OF THE INVENTION

The device of the invention includes a memory array with m word positions or storage locations, each word position consisting of n bits arranged in order of significance. The memory array has n cells for each word position in the memory array, or a total of mn cells. Each cell in a given word position includes a J-K type flip flop which stores the appropriate bit or character for the given word. For example, for a word 1010 stored in a given word position of the memory array, the assertion outputs of the J-K flip flop of the four cells of that word position would be 1, 0, 1, 0 starting with the cell of the most significant bit. Consequently, the corresponding negation outputs of these flip flops would be 0, 1, 0, 1, respectively. All cells of a given word position include common write, read (shift down) and shift up buses. All cells of a given bit position receive the assertion and negation outputs of the corresponding bit of a word located externally of the memory array which one desires to write into the memory array. Each of the cells comprises circuit logic for implementing an algorithm which will now be explained. Starting at the most significant bit, a comparison is made between the most significant bit of the external word and the most significant bit of

all words in the memory array. If there is a disagreement in a given word, the memory cell of the most significant bit of the given word position will produce a block level which is supplied to all succeeding cells in that word position. The second bit of the external word is compared in like fashion with the second bits of the words in the memory array, and so on, for other bits. A pattern of block levels thus will be established, each block level from the given cell being transferred to the cells of the same word position and all bit positions of lower significance.

In writing an external word into the memory array, a control level is supplied to the cell of the most significant bit and least significant word position. The logic circuitry in this cell is such that, if a given bit of the external word is ZERO, the control level will be transferred across the cell to the cell of the next least significant bit in that word position. In other words, the cell logic circuitry is such that, if a given bit of the external word is ZERO, the control level will move across exactly one bit in the memory array without moving downward. If there is a one in a bit of the external word, the control level will be directed downwardly from the memory array cell corresponding to that bit and to that word position under consideration, and will be transferred to the cell of the same bit position and of the word position of next higher order of priority. The control level will continue to drop downwardly through all cells of that bit position until it either meets a cell in that bit position in the memory array which has a ONE in it or it meets a cell which contains a block level. When either of these conditions occur, the control level is transferred to the cell of the next least significant bit in that word position. In other words, if there is a ONE in the external word, the control level will drop until it either meets another ONE in the memory array or encounters a block, at which point the control level moves across one bit in the memory array.

The control level, after following a path through the memory array which will differ for different combinations of external word and words stored in the memory array, will emanate from a word position of the memory array which is of immediately higher priority than the word position into which the external word should be written. The control level thus emanating from the storage array then is used to energize the write bus of the cells in the word position immediately preceding that from which the control level has emanated. The level on the write bus, together with the assertion or negation output from the cell of the external memory word bits, will enable a gate for actuating either the J or K input to the flip flop of that cell. The control level emanating from a cell in a given word position is applied to the shift up buses of cells of all word positions preceding the word position to be written into. The level on the shift up buses, together with either the assertion or negation output from the J-K flip flops of these cells will enable a gate for actuating either the J or K input to the preceding flip flop, depending upon the bit of the word to be shifted. Upon arrival of a clock pulse, transfer of words in all word positions preceding the word position written into the immediately preceding word position is accomplished. The characteristics of the clocked J-K flip flop of the cells is such that the words can be shifting directly and non-destructively from one word position to the adjacent word position without need for such devices as dummy registers. When it is desired to read a word from the memory array, a read level is applied to the shift down buses of the cells of all word positions and the read level on the shift down bus, together with either the assertion or negation output from

the cell of the immediately preceding word position will enable the gate actuating either the J or K input to the flip flop of the corresponding cell depending upon the bit of the word to be shifted. Upon arrival of a clock pulse, transfer of all words to the succeeding word position is accomplished.

Summarizing, each word to be written into the memory array is inserted in the word position thereof which depends upon the priority of that word and those already within the memory array. The words are written into the memory array in their proper order of priority. When the memory array becomes full, an additional word to be written in must displace one of the words already in the full array. This new word will be written into the proper position in the order of priority and the word of lowest priority will be shifted off. When it is desired to read a word from the memory array, this may be done simply by applying the read level to the cells of the memory array, thereby shifting all words in the memory array one word position. The word nearest the output end of the memory array (the word of highest priority) will then be transferred into an output register. The next read level will transfer the word of next higher priority, which will be the word shifted into the word position of highest priority to replace the word previously read out.

BRIEF DESCRIPTION OF THE DRAWINGS

FIGS. 1A and 1B is a schematic diagram illustrating an embodiment of a priority sequencing device according to the invention; and

FIG. 2 is a diagram showing the contents of a conventional cell used in the system of FIGS. 1A and 1B.

DESCRIPTION OF THE PREFERRED EMBODIMENT

In the example illustrated, it will be assumed that each priority word has four bits and that the memory array has a capacity of six priority words. The number of bits needed will depend on the number of word positions in the memory array. It should be understood that each priority word forms a portion of a complete word which may have any number of bits, including operation codes, and information bits. In other words, each word stored in the computer memory contains many bits of which four (in this example) serve to indicate the priority of that word. In order to simplify an examination of this application, only the priority indicating portion of the complete word, hereinafter referred to as the priority word, will be discussed. Whenever a priority word is transferred from one position to another in the memory array, it should be understood that the remaining portion of the word will shift along with the priority word.

For the sake of illustration, it will be assumed that the bits of the priority word from some external control unit are loaded into an external memory comprising registers IN1, IN2, IN3, and IN4 such that the register IN1 will contain the most significant priority bit and the register IN4 will contain the least significant bit. The word position nearest the input will be referred to as the first word position. The words are written from the external memory into the memory array 10 from top to bottom, in the illustration given, so that if the memory array is empty, the first word will be written into the last (in the example shown, the sixth) word position. As a result of the priority scheme of the invention, the word with the highest priority will be found in the sixth word position comprising cells E₆₁, E₆₂, E₆₃ and E₆₄. Similarly, the word with the next highest priority will be found in the penultimate (fifth) word position comprising cells E₅₁, E₅₂, E₅₃ and E₅₄, while the word with lowest priority (or, in the case of equal priority, the word last written into the memory array) will be located in the first word position which comprises cells E₃₁, E₃₂, E₁₃ and E₁₄.

The first arabic numeral in the cell designation represents the word position, while the second numeral represents the bit position. For example, cell E₃₄ is the cell of the third word position and the fourth (most significant) bit in the third word position. In referring generically to a cell E_{mn}, m is the word position and n is the bit position.

As a means for arriving at the desired circuit logic for implementing the priority positions, an algorithm has been derived. An arbitrary group of ordered binary coded bits is shown in Table I.

TABLE I

External Word	0	1	1	1
1st Word in Memory Array	0	0	---	0
2nd "	"	0	0	---
3rd "	"	0	1	0
4th "	"	0	1	1
5th "	"	1	---	0
6th "	"	1	---	0

The uppermost 4-bit word represents the external priority word to be written into the memory array. The line and arrow thereon illustrates the path building of the external word through the memory array. In order to explain the technique for path building, comparison between the external word and the memory array must be established. The algorithm is as follows:

Starting at the most significant bit, a comparison is made between the first bit of the external word to be written into the memory array and the first bit of the first word in the memory array. If a word position in the memory array is empty, the registers of the bits of that word position will arbitrarily be set to zero, one (an assertion output of zero). If there is a disagreement between the first bit of the external priority word and the first bit of the first word in the memory array, said memory array bit receives a block. This block is indicated in Table I as a dash to the right of the bit. All following bits of that same memory array word will also receive blocks. The next comparison is made between the first bit of the external word and the first bit of the second word in the memory array, and so forth across the memory array. Similarly, the second bit of the external priority word is compared with the various second bits of the memory array. When the entire memory array has been thus examined and the necessary blocks inserted, a bit may now be directed through the memory array to accommodate the external word.

If the external bit is a zero, the path will move across exactly one bit without moving down. If, on the other hand, there is a one in the external word, the path will drop until it either meets another one in the memory array or encounters a block. At this point, the path moves across one bit. The path across moves over the block or bit being compared.

Before describing the basic system of FIG. 1 in detail, reference will be made to FIG. 2 which is a schematic representation of a cell E_{mn} of the memory array. First of all, however, it should be pointed out that there are some modifications made in certain of these cells. For example, all cells of the first word position, namely, cells E₁₁, E₂₁, E₃₁, E₄₁, E₅₁ and E₆₁ have no B input to gates L and Z. Finally, all cells of the fourth bit position, namely, cells E₁₄, E₂₄, E₃₄, E₄₄, E₅₄ and E₆₄, need have no G, H and Z gates, since there is no need for B* outputs from these cells. Cells E₂₂, E₂₃, E₃₂, E₃₃, E₄₂, E₄₃, E₅₂ and E₅₃ are exactly as shown in FIG. 2.

The lines A_n and $\bar{A}_n$ to the cell E_{mn} carry available assertion and negation outputs of the external word register corresponding to the nth bit. For example, if the word in the external register 11 were 0111, the A_n and

the $\bar{A}_n$ levels from external registers IN2, IN3 and IN4 would be one and zero, respectively, while the A_n and $\bar{A}_n$ levels from external register IN1 would be zero and one respectively. The A_n and the $\bar{A}_n$ levels are supplied to all memory cells of the n th bit.

Also entering each cell E_{mn} except for first word cells as previously indicated, is a D line which is connected to the D^* output line of the cell of the same bit position but of the immediately preceding word position; that is, line D of cell E_{mn} is connected to the D^* output of cell $E_{(m-1)n}$. Likewise, each cell E_{mn} , except for the first bit cell, includes a B and a C input line which is connected to the respective B^* and C^* output lines of the cell of the same word position but of the immediate preceding bit position. In other words, lines B and C of cell E_{mn} both are connected to cell $E_{(m-1)n}$.

Each cell E_{mn} includes a register F which may be in the form of a J-K flip flop having J and K input lines and corresponding output lines Q_{mn} and $\bar{Q}_{mn}$. These output lines proceed from cell E_{mn} and are connected to input lines $Q_{(m+1)n}$ and $\bar{Q}_{(m+1)n}$, respectively, of cell $E_{(m+1)n}$; in the case of the last word cell, the output lines Q_{mn} and $\bar{Q}_{mn}$ are connected to the appropriate input lines of output registers OP1, OP2, OP3 and OP4. The $Q_{(m+1)n}$ and $\bar{Q}_{(m+1)n}$ lines from cell $E_{(m+1)n}$ are connected to AND gates I and VI, respectively, of cell E_{mn} . The other input to gates I and VI is connected to the SHIFT UP bus L_{um} of cell E_{mn} . The $Q_{(m-1)n}$ and $\bar{Q}_{(m-1)n}$ lines from cell $E_{(m-1)n}$ are connected to AND gates II and V, respectively. The other input to gates II and V are connected to SHIFT DOWN but L_{dm} of cell E_{mn} .

The input lines A_n and $\bar{A}_n$ are connected to respective AND gates III and IV of cell E_{mn} . The other inputs to gates III and IV is connected to the WRITE bus L_{wm} of cell E_{mn} . It will be noted that there is a separate SHIFT UP, SHIFT DOWN and WRITE bus for each word position of the memory array and that a given one of these lines passes through all cells of a given word position.

The output line of AND gates I, II, and III of cell E_{mn} are connected to an OR gate R and the output line of OR gate R is connected to the J side of flip flop F for cell E_{mn} . Similarly, the output lines of AND gates IV, V and VI of cell E_{mn} are connected to an OR gate S and the output line of OR gate S is connected to the K side of flip flop F of cell E_{mn} .

A clock pulse CL is applied simultaneously to the flip flop F of all of the cells of the memory array 10 and any state transformations of a flip flop occur only upon receipt of such a clock pulse. The clock pulse may be derived from a single clock source 12 and can be applied to all flip flops by closing switch 13 at some interval following either movement of switch 15 to the READ or WRITE position.

If any of the following three conditions is met, a level will be available at a corresponding input or OR gate L of a given memory array cell E_{mn} . The first condition is the n th bit of the external word is a zero; if this condition exists, there will be an input level $\bar{A}_n$ on input line a of OR gate L of cell E_{mn} and also to other input lines a of n th bit cells. The second condition is that the n th bit of the n th priority word at cell E_{mn} is a one; if this condition exists, there will be an input level Q_{mn} on input line q of OR gate L of cell E_{mn} . The third condition is that the bit on line A_n of the external word, if any, and the same bit in the cell E_{mn} of the memory array are different bits, there will be an input level B on input line b of OR gate L of cell E_{mn} .

An OR gate P is receptive of either (but never both) a C level from the cell $E_{(m-1)n}$ and of a D level from cell $E_{(m-1)n}$. The output on line P1 of OR gate P is applied to an AND Gate X which also receives the output of OR Gate L by way of line L_1 . The output, if any, from OR gate X is referred to as C^* . The condition for a C^*

level from any cell in the memory array then may be expressed by the following logical equation:

$$C^* = (C_{mn} + D_{mn})(Q_{mn} + \bar{A}_{mn} + B_{m(n-1)})$$

5 were $B_{m(n-1)}$ is the blocking level, if any, gate Z of the cell $E_{m(n-1)}$ presented to cell E_{mn} , Q_{mn} is the affirmation output from flip flop F of cell E_{mn} and $\bar{A}_{mn}$ is the negation output of the external word bit A_n presented to cell E_{mn} and C_{mn} and D_{mn} (only one of which is obtained for a given cell) are the levels obtained from the immediate preceding cell $E_{m(n-1)}$ and $E_{(m-1)n}$, respectively.

If one or more of three conditions is met, no level will appear at any of the inputs to OR gate L of cell E_{mn} . Firstly, if there is a ONE in the n th bit A_n of the external priority word, there will be no input on input line a of OR gate L of cell E_{mn} . Secondly, if there is a ZERO in the n th bit of a word in the n th position of memory array 10, there will be no input on input line q of OR gate L of cell E_{mn} . Thirdly, if there is disagreement between the $(n-1)$ th bit in the external word and the corresponding $(n-1)$ th bit of the word in the memory array, that is, if one bit is a one and the other bit is a zero, there will be no input on line b of OR gate L of cell E_{mn} . The preceding remarks can be restated as follows: If all three of the following conditions occur simultaneously, there will be no output from gate L. First, the n th bit from the external memory is a one; second, Q_{mn} is a zero; and third, A_n and Q_{mn} are different binary characters.

30 If the blocking level presented to a given cell E_{mn} of the memory array 10 is represented by B from the cell $E_{m(n-1)}$, $\bar{Q}_{mn}$ is the negation output of the flip flop from cell E_{mn} and A_n is the affirmation output from the flip flop of the n th bit of the external word presented to cell E_{mn} , the condition for a D^* level from cell E_{mn} then may be expressed by the following logical equation:

$$D^* = (C + D)(Q_{mn}A_n\bar{B}_{m(n-1)})$$

where C and D are the input levels to cell E_{mn} obtained from one or the other (but not both) of the respective output gates X and Y of the cell $E_{(m-1)n}$ or cell $E_{m(n-1)}$, as the case may be.

40 Whenever the Q output of flip flop F of cell E_{mn} is a ONE and the n th external word bit is a ZERO, AND gate G will be enabled, as also will be OR gate Z, and a B^* output will be obtained at cell E_{mn} . On the other hand, the output of the flip flop F to cell E_{mn} is a ZERO and the n th digit of the external word is a ONE, AND gate H is enabled, as is also gate Z; again a B^* output is obtained at cell E_{mn} , this input also will enable OR gate Z and a B^* output will be obtained at cell E_{mn} . This is in line with the statement made previously that a block pulse, once obtained, is produced for all other bits of the word in the memory array.

45 If either a C or D pulse level appears at cell E_{mn} and an output is available at OR gate L, under conditions already described, AND gate X is enabled and a C^* output is available at cell E_{mn} . If, however, there is no output at OR gate L coincidentally with the presence of either a C or D level at cell E_{mn} inhibit gate Y is enabled and a D^* output is obtained at cell E_{mn} . It will be noted that only one of the gates X and Y of any particular cell E_{mn} can be enabled at any time. In other words, if a C^* level emanates from gate of cell E_{mn} , there can be no D^* level emanating via gate Y of the same cell. The decision as to which path through a cell in word position m and bit position n in the control level from generator 17 will pass will be determined on the basis of comparison of the n th bit in the external priority word and the corresponding n th bit of the word m in the memory array.

50 When it is desired to SHIFT information down the memory array, switch 15 is moved to the READ position and a one level from generator 17 is supplied to all SHIFT DOWN lines of the memory array. In order to explain the SHIFT DOWN or READ operation, it will be assumed that the last (sixth) word position in the memory

array contains the word 0101 and that it is desired to READ this word out of the memory array into the output registers OP1 to OP4. It will further be assumed that the preceding word position (fifth position) of the memory array is empty. Consequently, the aforementioned outputs of the flip flops of the fifth word position of the memory array will be 0000. If, now, the READ (SHIFT DOWN) line L_{dm} is energized by moving switch 15 to the READ position, the operation will be as indicated in the following Table III. As an aid in explaining Table III, Table II will first be presented showing the operation of the J-K flip flop in the various cells of the memory array.

TABLE II

Initial State Q	Input Signal			Resulting
	J	K		
1	1	0		1
1	0	1		0
0	1	0		1
0	0	1		0

TABLE III

Cell E_{mn}	Initial Q_{mn}	$Q_{(m-1)n}$	Bus Energized	Register AND Gate Enabled	Register OR Gate Enabled	FF Input Activated	Resulting Q_{mn}
$E_{61} \dots$	0	1	L_{dm}	V	S	K	0
$E_{62} \dots$	1	1	L_{dm}	V	S	K	0
$E_{63} \dots$	0	1	L_{dm}	V	S	K	0
$E_{64} \dots$	1	1	L_{dm}	V	S	K	0

Upon arrival of a clock pulse CL to the flip flops of the cells of the memory array, the affirmation outputs of all cells of the last (sixth) word position will be 0000, indicating that the priority word previously in the memory array (viz., 0101) has been read out of the memory array. The bits formerly in word position 6 then are transferred to corresponding output registers 01 to 04. The word 0000 remains at the sixth word position of the memory array until the next execution command level (SHIFT DOWN, SHIFT UP or WRITE) occurs at one of the buses L_{dm} , L_{um} or L_{wm} .

Having emptied the memory array, it will be assumed further that the priority word 1101 is to be written into the memory array. The switch 15 is placed in the WRITE position and the control level from generator 17 appears at the C input line of the first cell E_{11} . As previously noted, none of the other first bit cells have such a C input line. This C level from generator 17 forms an input to OR gate P of cell E_{11} , and, although cell E_{11} has no D input, an output level appears at output line P1 of OR gate P. A ZERO and a ONE is applied to gates II and V, respectively, of all first word cells. Gates II and V have received an input level from SHIFT DOWN line L_{dm} during the prior READ operation and the gates V and S are enabled. The K side of flip flop F of cell E_{11} will be activated upon receipt of clock pulse CL and Q_{11} and $\bar{Q}_{11}$ of cell E_{11} will be a ZERO and a ONE, respectively. Likewise, gates V and S of the first word cells E_{12} , E_{13} , and E_{14} will be enabled, the K side of the flip flops of these cells will be activated and Q_{mn} of these cells will be a ZERO. Since Q_{11} is ZERO, there is no input on line q of OR gate L of cell E_{11} . Likewise, there is no input on line q of gate L of cells E_{12} , E_{13} and E_{14} . Moreover, since the first bit from the external memory flip flop is a ONE, $\bar{A}_{11}$ is ZERO and there is no input on line a of OR gate L of cell E_{11} . The same is true for cells E_{12} , E_{13} and E_{14} . It should be noted that there

is no B input to any of the first bit cells of the memory array; hence, there is no input on line b of OR gate L of cell E_{11} . In other words, gate L of cell E_{11} is closed and no output appears on OR gate line L1. It follows that the AND gate X is not enabled and that no output level C* appears at cell E_{11} . Since there is an input on line P1 of AND gate Y, together with no input on inhibit line L1 of AND gate Y, conditions are proper for an output level to appear on output line Y1 of gate Y of cell E_{11} . Consequently, a level appears at the D* output line from cell E_{11} .

The incoming control level from generator 17 thus moves downwardly from cell E_{11} and is transferred to the first bit cell E_{21} of the second word position. In other words, the D* output from cell E_{11} now becomes a D input to cell E_{21} and passes OR gate P of cell E_{21} . Since Q_{11} , Q_{12} , Q_{13} and Q_{14} are all ZERO, there can be no output from AND gate G of respective cells E_{11} , E_{12} , E_{13} and E_{14} . Likewise, since A_1 , A_2 , A_3 and A_4 are all ZERO, there can be no output from AND gate H of

respective cells E_{11} , E_{12} , E_{13} and E_{14} . With no input from line b of OR gate Z of cell E_{11} , there can be no B* output from cell E_{11} . Consequently, there is no B input to cell E_{12} or to cells E_{13} and E_{14} and there can be no input to line b of OR gate L of cells E_{12} , E_{13} and E_{14} . In other words, OR gate L of cells E_{12} , E_{13} and E_{14} is closed and OR gate Y of these cells necessarily is closed. The input control level from generator 17, therefore, cannot cross cell E_{11} to any of the other cells E_{12} , E_{13} and E_{14} of the first word position, since gate X of these cells is closed. Since the flip flops of all cells have been reset to the ZERO condition as a result of previously reading out all words from the memory array, the Q output of cell E_{21} is ZERO and no input appears on line q of gate L of cell E_{21} . Since the first bit of the external word is a ONE, the level at line $\bar{A}_1$ is a ZERO and there is no input on line a of gate L of cell E_{21} . There is no B input to cell E_{21} . Therefore, OR gate L of cell E_{21} is closed and, as in the case of cell E_{11} , the AND gate X of cell E_{21} is closed and gate Y of cell E_{21} is enabled. An output D* thus emanates from cell E_{21} and is transferred by way of input line D of cell E_{31} to the OR gate P of cell E_{31} .

It is now evident that there will be no output on line L1 of OR gate L of cells E_{31} , E_{41} , E_{51} and E_{61} , since all Q_{mn} outputs of these cells are ZERO, the $\bar{A}_1$ input to all of these cells is ZERO and there is no B input to any of these cells. Consequently, the AND gate X of all these cells will be closed and the AND gate Y of all these cells will be enabled. As a result, the control level from generator 17 proceeds down through all of the first bit cells of the memory array and emanates from the D* line of cell E_{61} . This D* output passes OR gate T and energizes the WRITE bus L_{w1} of the first word position. The writing operation may be described by reference to Table IV.

TABLE IV

Cell E_{mn}	Priority Word Bit A _n	Initial Q_{mn}	Bus Energized	AND Gate Enabled	OR Gate Enabled	F Input Activated	Resulting Q_{mn}
$E_{61} \dots$	1	0	L_{w1}	III	R	J	1
$E_{62} \dots$	1	0	L_{w1}	III	R	J	1
$E_{63} \dots$	1	0	L_{w1}	III	R	J	1
$E_{64} \dots$	0	0	L_{w1}	IV	S	K	0

Initially, the word 0110 is stored in word position four of the memory array. In other words, the active lines from the cells of E_{41} , E_{42} , E_{43} and E_{44} are $\overline{Q}_{41}$, Q_{42} , Q_{43} and $\overline{Q}_{44}$, respectively. These outputs become inputs to the respective cells of the immediately preceding (third) word position; that is, the Q outputs of cells E_{41} , E_{42} , E_{43} and E_{44} become the Q inputs to AND gates I or VI of respective cells E_{31} , E_{32} , E_{33} and E_{34} . The SHIFT UP bus L_{u3} also provides an input to AND gates I and VI of cells E_{31} , E_{32} , E_{33} and E_{34} . The gates VI and S of cells E_{31} and E_{34} are enabled and a K input occurs at the flip flop F of cells E_{31} and E_{34} . Similarly, gates I and R of cells E_{32} and E_{33} are enabled and a J input occurs at the flip flop F of cells E_{32} and E_{33} . Since the word stored in the third word position of the memory was 0101, we have the following flip flop operation table.

TABLE VII

Cell	Initial Q _{3n}	Input		Resulting Q _{3n+1}
		J	K	
E ₃₁ -----	0	0	1	0
E ₃₂ -----	1	1	0	1
E ₃₃ -----	0	1	0	1
E ₃₄ -----	1	0	1	0

It is evident that the flip flop of cell E_{33} of the third word position has changed state, so that the word now appearing in the third word position is 0110. This is the word that previously was in the fourth word position; in other words, the word previously in the fourth word position has been shifted up to the third word position of the memory array.

Similarly, the word 0010 in the third word position must be shifted up to the second word position. This is done by placing the control level from C* line of cell E₅₄ on SHIFT UP bus L_{u2} of the second word position by way of OR gates U₁, U₂ and U₃. Now the inputs to the AND gates I and VI of cells E₂₁, E₂₂, E₂₃ and E₂₄ emanating from respective cells E₃₁, E₃₂, E₃₃ and E₃₄ are 0, 1, 0 and 1. Consequently, gates VI and S of cells E₂₁ and E₂₃ are enabled and the K side of the flip flop of these two cells is activated. Likewise, gates I and R of cells E₂₂ and E₂₄ are enabled and the J input of the

flip flop of these cells is activated. The following operation Table VII then obtains:

TABLE VIII

Cell	Initial Q_{2n}	Input		Resulting Q_{2n}
		J	K	
E_{21} -----	0	0	1	0
E_{22} -----	0	1	0	1
E_{23} -----	1	0	1	0
E_{24} -----	0	1	0	1

10 The resulting word now in the second word position
is 0101. This is the word that was in the third word
position, indicating that the word in the third word position
has been shifted up one word position to the second
15 word position.

It is now evident that the word formerly in the second word position, namely, 0010, will be shifted up to the first word position owing to the arrival at SHIFT UP bus L_{u1} of the control level from the C^* output of cell E_{54} by way of gates U1 to U4. The word formerly in the first word position, that is, the word of lowest priority, now is removed from the memory array.

If the external word to be written into the memory array is of the same priority as that of a given word already in the memory array, it can be shown that the external word will be read into the memory word position immediately preceding that occupied by said given word. In other words, a word of a given priority already in the memory array takes precedence over the external word of equal priority. This can be shown by means of the algorithm chart of Table VIII and Table IX.

TABLE VIII

External Word	0	1	0	1
1st Word in Memory Array	0	0	0	1
2nd "	0	0	1	0
3rd "	0	1	0	1
4th "	1	0	0	0
5th "	1	0	1	0
6th "	1	1	1	0

TABLE IX

	G_{mn}	H_{mn}	B_{mn}	B^*_{mn}	C_{mn}	D_{mn}	P_{mn}	L_{mn}	G^*_{mn}	D^*_{mn}

E ₆₂	1	0	0	1	1	0			0		0	0	0	0	1	0	0	0	0	0	0	0
E ₆₃	1	0	1	0	0	0			0		0	0	0	0	1	0	0	0	0	0	0	0
E ₆₄	0	1	1	0	X	X			0		X	0	0	0	0	1	0	0	0	0	0	0

In other words, the Q_{6n} outputs of cells E_{61} , E_{62} , E_{63} and E_{64} of the sixth word in the memory array are 1, 1, 1 and 0, respectively, indicating that the word 1110 originally in the external memory IN1-IN4 has been written into the last word position of the memory array.

In accordance with the invention, if a priority word of lower priority were to be made available at the external memory IN1 to IN4, this word, upon receipt of the next WRITE signal from generator 17 and triggering by the succeeding clock pulse CL, would be transferred into the fifth word position of the memory array, that is, the memory position immediately above the priority word already in the sixth or last word position of the memory array. This process would be repeated so long as successive priority words were presented to the external memory, in their order of priority, until all word positions of the memory array are filled.

It will now be assumed that the first through sixth word positions of the memory array have been filled with priority words in the following order 0001, 0010, 0101, 0110, 1010, and 1110, and that the priority word loaded into the external memory which is to be written into the memory array is 0111. The manner in which the control level from generator 17 passes through the memory array can be shown by resort to Table V.

directly to the WRITE bus L_{W4} of the word position (fourth position) immediately preceding the word position (fifth position) from which the control signal emanates.

At this time, all other WRITE buses L_{w1} to L_{w3} , L_{w5} and L_{w6} will be inactive since none of the cells E_{41} , E_{42} , E_{43} , E_{44} and E_{64} will have C^* outputs. With the WRITE bus L_{w4} active, and with ZERO input at line A_1 , gate IV of cell E_{41} will be enabled, and an input control level will be applied by way of gate S to the K input of flip flop F of cell E_{41} . Since the Q output of the flip flop F of cell E_{51} was a ZERO, the K input to the flip flop of cell E_{41} will not change the state of the flip flop and the Q output will remain a ZERO. Similarly, with a ONE input at lines A_2 and A_3 feeding cells E_{42} and E_{43} gate III of these cells will be enabled and an input control level will be applied by way of OR gate R of cells E_{42} and E_{43} to the J input of the flip flop of cells E_{42} and E_{43} . Since the Q output of the flip flops of cells E_{42} and E_{43} were ONES, the Q input from cells E_{42} and E_{43} will remain ONES. Finally, with a ONE input at line A_4 to cell E_{44} , gate III of cell E_{44} is enabled and an input level is applied by way of Gate R to the J input of the flip flop of cell E_{44} . Since the Q output from the flip flop of cell E_{44} was a ZERO, this flip flop will change state and its Q output will be

The dashes in the table indicate that no physical inputs can exist and the crosses indicate that no physical outputs are possible. For example, there are no D inputs to cells of the first word position, namely, cells E_{11} , E_{12} , E_{13} and E_{14} . For this reason, AND gate P is superfluous. In the case of cell E_{11} , the level from signal generator 17 can be applied directly over C line of cell E_{11} to gates X and Y of that cell. In the case of all cells of the first (most significant) bit, except for cell E_{11} , there are no C inputs; therefore, any D input can be applied directly to the gates X and Y of that cell. In the case of all cells of the fourth (least significant) bit, there is no need for a block level B^* ; consequently, gates G, H, and Z may be omitted and the absence of any output therefrom is indicated in the Table V by the crosses. It can be seen from Table V that the control signal level appears successively at the C^* output of cell E_{11} , the D^* output of cell E_{12} , the D^* output of cell E_{22} , the C^* output of cell E_{32} , the D^* output of cell E_{33} , the C^* output of cell E_{43} , the D^* output of cell E_{44} and the C^* output of cell E_{54} . The path through the memory array is indicated by the heavy dashed line. The control signal at output line C^* of cell E_{54} is applied

55 come a ONE. The present Q outputs of cells E_{41} , E_{42} , E_{43} and E_{44} , then, are 0, 1, 1 and 1, respectively. In other words, the word 0111 from the external memory has been written into the fourth word position of the memory array. This obviously is the correct position for the word 0111 since 0111 is of greater weight than the first four words in the memory array (viz., words 0001, 0010, 0101 and 0110) but of lesser weight than the words 1010 and 1110 in word positions five and six of the memory array.

65 Since the word 0111 from the external memory has been written into the fourth word position, it obviously is necessary to shift up the words in the first four word positions of the memory array. This is accomplished by energizing the SHIFT UP buses L_{u4} , L_{u3} , L_{u2} and L_{u1} . The control level emanating from the C^* line C^{*54} of cell E_{54} passes OR gage $U2$ enroute to SHIFT UP bus L_{u5} of the third word position of the memory array. This C^* output of cell E_{54} also passes through OR gates $U2$ and $U3$ enroute to SHIFT UP bus L_{u2} of the second word position of the memory array and via OR gates $U2$, $U3$ and $U4$ to the SHIFT UP bus L_{u1} of the first word position.

The Tables VIII and IX indicate, by way of example, that, for an external word 0101 and a priority word 0101 already in the third word position of the memory array, the control level from generator 17 will proceed across cell E_{11} to cell E_{12} , down cell E_{12} to cell E_{22} , down cell E_{22} to cell E_{32} , across cell E_{32} to cell E_{33} , across cell E_{33} to cell E_{34} and across cell E_{34} to the C^* output line thereof. The control level from generator 17 then appears on the WRITE bus L_{w2} of the second word position of the memory array. Upon arrival of the next clock pulse CL to the flip flops of cells E_{21} , E_{22} , E_{23} and E_{24} , these flip flops will be actuated and the word 0101 from the external memory will be written into the second word position. Likewise, the control level from the C^* line of cell E_{34} will pass through gate U4 to the SHIFT UP line L_{u1} of the first word position to shift the word 0010 formerly in the second word position to the first word position and, in effect, shifting the word 0001 off the memory array.

This completes the description of the preferred embodiment of the invention illustrated herein. However, many modifications thereof will be apparent to those skilled in the art. Accordingly, it is desired that the invention not be limited by the particular details of the embodiment described herein except as defined by the accompanying claims.

What is claimed is:

1. A priority sequencing device comprising a *priority* memory array having a storage capacity of m priority words, said memory array including mn cells where m is the number of priority word positions in said array and n is the number of priority bits per memory word, external storage means into which is loaded an external priority word to be presented to said memory array, means for applying a control level to the cell of the lowest priority memory word position and of the most significant bit, said cells each including logic circuitry for controlling the path through the cells of said memory array taken by said control level and also the memory word position from which said control level emanates from said memory array in accordance with the relative priority of the aforementioned memory words.

2. A priority sequencing device according to claim 1 wherein the memory cells except those for the least significant bit each have a first output line connected to the cells of the same memory word position and of the bit of next lower significance, and the memory cells except those for the memory word position of lowest priority having a second output line connected to the cell of the same bit and of the memory word position of next higher priority.

3. A priority sequencing device according to claim 2 further including a set of execution command lines for the cells of each of said memory word positions, the control level emanating from said array energizing one of said command lines of the immediately preceding memory word positions for writing said external words into the latter position, and the control level emanating from said array energizing another of said command lines of all

memory word positions preceding the memory word position written into for shifting the contents of all said preceding memory word positions to an adjacent memory word position nearer the external storage means.

5 4. A priority sequencing device according to claim 3 further including means for deriving a block level at a cell of a given bit in the memory array and at cells of bits of lower significance in the same memory word position wherein said given bit disagrees with the corresponding bit of the word in the external memory, said block level preventing transfer of said control level to said second output line.

10 5. A priority sequencing device according to claim 4 further including means for transferring said control level incident on a cell of a given bit to the first output line thereof when the corresponding bit of the external word is a zero, and means for transferring said control level incident on a cell of a given bit to the second output line thereof when the corresponding bit of the external word is a ONE and when there is no block level at said cell.

15 6. A priority sequencing device according to claim 1 further including a set of execution command lines for the cells of each of said memory word positions, the control level emanating from said array energizing one of said command lines of the immediately preceding memory word positions for writing said external words into the latter position, and the control level emanating from said array energizing another of said command lines of all memory word positions preceding the memory word position written into for shifting the contents of all said preceding memory word positions to an adjacent memory word position nearer the external storage means.

20 7. A priority sequencing device according to claim 6 further including means for deriving a block level at a cell of a given bit in the memory array and at cells of bits of lower significance in the same memory word position wherein said given bit disagrees with the corresponding bit of the word in the external memory, said block level preventing transfer of said control level to said second output line.

25 8. A priority sequencing device according to claim 7 further including means for transferring said control level incident on a cell of a given bit to the first output line thereof when the corresponding bit of the external word is a zero, and means for transferring said control level incident on a cell of a given bit to the second output line thereof when the corresponding bit of the external word is a ONE and when there is no block level at said cell.
